UNITED STATES PATENT OFFICE.

ELAM A. GROSS, OF CAMDEN, NEW JERSEY.

RAILWAY-BRIDGE INDICATOR.

SPECIFICATION forming part of Letters Patent No. 289,770, dated December 4, 1883.

Application filed July 6, 1883. (No model.)

To all whom it may concern:

Be it known that I, ELAM A. GROSS, a citizen of the United States, and a resident of Camden, in the county of Camden and State 5 of New Jersey, have invented certain new and useful Improvements in Railway-Bridge Indicators; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of the apparatus 15 in its operative position, and Fig. 2 is an end view of the same.

Similar letters of reference indicate corresponding parts in both the figures.

The object of my invention is to prevent injury to train-men when riding on the top of 20 box-cars in passing under bridges. As is well known, it rarely happens that a railway-bridge is at a sufficient elevation above the roof of cars to permit a person standing on the car to 25 pass under the bridge, and on dark nights, when the bridge cannot readily be distinguished, serious injuries, and even loss of life, are often caused by the train-men being knocked off of the cars as the train passes under a bridge or enters a tunnel.

My invention consists in an inexpensive but effective indicator, whereby the approach to a bridge or tunnel is indicated some distance ahead, so that the train-men may have an opportunity of either leaving the roof of the 35 cars, or, by placing themselves in a recumbent position, enabling them to pass under the bridge without injury.

The nature of my invention will be readily 40 understood by reference to the accompanying drawings, on which A represents a post or upright of suitable height—say about twenty-one feet—which is firmly planted in the ground on one side of the bridge or tunnel and at a 45 suitable distance ahead of the same. At the upper end of the post A, and suitably braced thereto, is an arm, B, which extends across the track at right angles—say about eight feet in length, more or less. This arm is provided 50 on its under side with a series of staples or eye-screws, C, placed at a distance apart of about a foot, more or less. Fastened into

these staples are sections of thick wire D, about two feet in length each, to the lower ends of which are affixed bells E, which may be of any 55 approved construction. To the bells again are attached other wires, F, about three feet in length, movably suspended from or hinged to the same in any suitable manner.

From the foregoing description, taken in 60 connection with the drawings, the operation of this device or apparatus will readily be understood without requiring extended explanation. As a train approaches a bridge or the entrance of a tunnel, persons standing on top 65 of the freight-cars or box-cars will come in contact with the lower wires, F, which will ring the bells, and thereby give warning that a bridge or tunnel is being approached, which warning is given a sufficient time ahead to enable the men to descend from the cars or to lie down flat. The wires being loosely suspended from the bells, and these again being loosely suspended from arm B, a person will 70 suffer no injury whatever by contact against 75 the loose wires.

Having thus described my invention, I desire it to be understood that I do not limit myself to any particular means for suspending the wires and bells, as other methods may be 80 employed which will answer the same purpose. For example, a rope or wire may be strung across the track between trees or posts on opposite sides, and the wires D may be fastened to this instead of to the arm B, extending laterally from the post, as in the drawings.

What I claim, and desire to secure by Letters Patent of the United States, is—

1. A device for indicating the approach to 90 bridges or tunnels on railway-tracks, consisting of a series of wires suspended transversely across and above the track and suitably fastened ahead of the bridge or tunnel, provided with bells or other suitable sonorous alarms 95 at their lower ends, and with depending wires adapted to operate said bells or alarms when struck by a person or persons standing on the roof of the cars, substantially as and for the purpose shown and set forth.

2. The herein-described safety device for indicating the approach to bridges or tunnels on railway-tracks, which consists in the post or upright A, having arm B, extending trans-

versely across and at a suitable distance above the track, and provided with staples or similar fastenings, C, wires D, bells E, and wires F, extending downwardly from the bells and 5 adapted to ring the same when brought in contact with a person or persons standing on the roof of a train of passing cars, substantially as and for the purpose shown and set forth.

In testimony that I claim the foregoing as my own I have hereunto affixed my signature to in presence of two witnesses.

ELAM A. GROSS.
